UNITED STATES PATENT OFFICE.

CHARLES TRACHTENBERG, OF BROOKLYN, NEW YORK.

SUITCASE, ETC.

Application filed November 30, 1923. Serial No. 377,679.

To all whom it may concern:

Be it known that I, CHARLES TRACHTENBERG, a citizen of the United States, and a resident of the borough of Brooklyn, 5 county of Kings, city and State of New York, have invented certain new and useful Improvements in Suitcases, Etc., of which the following is a specification sufficient to enable those skilled in the art to 10 utilize the same.

While my improvements are applicable to hand satchels, valises, portmanteaus, and analogous types of portable receptacles generally, they are designed more particularly 15 for use in conjunction with suit cases, so called in the trade; the object being primarily to provide detachable means for the support of a tray or equivalent auxiliary device; and secondarily to provide a tray 20 which is foldable in box shape and adapting it for use as a vanity case, or separate container, all as hereinafter fully set forth,—the invention consisting in the specific construction, combination and arrangement of 25 parts and appurtenances described and claimed, and a distinctive feature being the use of a plurality of detachable longitudinal shelf-bars for the support of said removable container.

30 I have herein exemplified a practical embodiment of the essential feature of my invention in a portable hand suit case of a well known type, although I do not confine myself to the identical configuration of parts 35 shown, since modifications in minor details, and equivalent mechanical expedients, may be resorted to with like results, and without departing from the spirit and intent of my invention in this respect.

40 With this understanding,

Fig. 1, represents a perspective view of my improved suit case, with the cover raised, and the foldable box tray fully extended in position;

45 Fig. 2, is a similar view, with the foldable box tray closed upon itself but supported on the shelf-bars within the body of the case;

Fig. 3, is a perspective view of one of the 50 shelf-bars, broken away centrally;

Fig. 4, is a perspective view, like unto Figs. 1 and 2, without the foldable box tray;

55 Fig. 5, is a perspective view of the foldable box tray removed from the suit case and partly opened up;

Fig. 6, is a central longitudinal section

of the suit case closed, with the foldable box tray also closed, and in position within the casing.

The body portion B, of the case or receptacle is of the usual elongate rectangular shape, and is provided with the ordinary cover C, hinged thereto, and is otherwise furnished with the customary adjuncts, such as a handle h, and fastening devices f, in a 60 manner well known in the art.

S, S, are the longitudinal shelf-bars, two or more of which may be used to afford adequate means for the support of the removable tray T. The extremities of each 70 of the said shelf-bars S, S, are formed with shouldered end bearings s, s, for engagement with the inner sides and edges of the end members b, b, of the case B, as shown more particularly in Figs. 2 and 4, of the drawings. Each shelf-bar S, is also formed with a truss-flange s', extending between the shouldered end bearings s, s, to stiffen and reinforce the flat upper or shelf surface s", of the bar S, which surface s", is for direct 75 contact with the under side of the tray T, as supported within the case body B. The shelf-bars may be made rectangular in cross section, thus affording both bearing surface 80 s", and truss-flange s'.

The tray T, is of novel construction in that it consists of two sections t', t", articulately connected at their medial upper edges t", and is provided with locking means t', t", whereby the two sections t', t", may be held 90 closed in box form,—thus constituting an auxiliary receptacle that may be used independently as a vanity box, or for any analogous purpose, when desired, without impairing its function as a tray as related to 95 the body portion B, of the case.

What I claim is my invention and desire to secure by Letters Patent is,

1. In a portable hand case, a support 100 adapted to rest upon the upper edges of opposite walls of the case, and a bodily-removable tray resting thereupon and formed of two sections articulately united directly to each other at adjacent walls to rest one upon the other in the same vertical plane.

2. In a portable hand case, a support adapted to rest directly upon the upper edges of opposite walls of the case, and a bodily-removable tray resting thereupon and formed of two sections articulately united 105 directly to each other at adjacent walls to rest the one upon the other in the same ver-

tical plane when folded, said support embodying a shelf and a depending truss flange.

3. In a portable hand case, a support adapted to rest directly upon the upper edges of opposite walls of the case, and a bodily removable tray resting thereupon and formed of two sections articulately united directly to each other at adjacent walls to rest the one upon the other in the same ver-

tical plane when folded, said support embodying a shelf and a truss flange depending therefrom, said tray being supported by said support in both the opened and closed condition of the tray.

CHARLES TRACHTENBERG.
